UNITED STATES PATENT OFFICE.

ERNEST HOPKINSON, OF EAST ORANGE, NEW JERSEY.

MACHINE FOR SERVING GLASS.

1,249,401.

Specification of Letters Patent. Patented Dec. 11, 1917.

Application filed January 3, 1913. Serial No. 739,999.

To all whom it may concern:

Be it known that I, ERNEST HOPKINSON, a citizen of the United States, and a resident of East Orange, county of Essex, and State 5 of New Jersey, have invented certain new and useful Improvements in Machines for Serving Glass, of which the following is a full, clear, and exact disclosure.

My invention relates to devices employed 10 for obtaining uniform molten masses of glass directly from a flowing stream thereof, and its object is to generally improve such devices and particularly to deposit the masses of glass directly into the molds or 15 other receptacles without the necessity of sustaining the stream while the molds or receptacles are being changed. Briefly stated, my invention comprises a series of receptacles or molds carried on a movable support, such as a rotatable table, the edges of 20 the molds having sharp edges, each of which constitutes one of the cutting members of the shearing device for severing the flowing stream of glass.

For a detailed description of one form of 25 my invention, reference may be had to the following specification and to the accompanying drawing forming a part thereof, in which:

Figure 1 is a vertical sectional view of 30 the carrier and cutting device, and showing the driving mechanism therefor in elevation;

Fig. 2 is a plan view thereof; and

Figs. 3 and 4 are detached sectional views 35 showing the cutting device in two positions relative to the receivers.

Referring to the drawing, the numeral 1 indicates the usual flow block which projects 40 from a glass furnace or tank. 2 is a standard or frame upon which the rotatable mold carrier 3 is pivoted. The receivers or molds 4 are mounted on the carrier 3 and in this instance their sides, which contact with each other, converge toward the center of the carrier 3 on radial lines. The upper edges of 45 the receivers 4 are beveled as shown at 5, so that when adjacent receivers come in contact, substantially sharp cutting edges are formed between the receivers, as clearly 50 shown in Figs. 1 and 3.

A reciprocating cutting member or knife 6 is mounted upon a longitudinally slidable bar 7 which carries at its lower end a cam roller or follower 8 which contacts with the 55 cam 9 on the horizontal shaft 10. The shaft 10 is connected with suitable driving mecha-

nism, and in this instance carries the fast and loose pulleys 11 and 12 around which may run a belt of the usual form.

The carrier 3 is advanced intermittently 60 between the cutting operations and for this purpose the spindle 13, to the upper end of which the carrier 3 is fixed, has attached to its lower end a screw gear 14 which meshes with the screw pinion 15 mounted on the 65 shaft 16. The shaft 16 also carries a slotted disk or star wheel 17 which coöperates with a pin or stud 18 projecting from a crank arm 19 on the shaft 10.

The cutting knife 6 and the edges 5 of the 70 receivers may be water-cooled should the same be found necessary.

The rotation of the shaft 10 reciprocates the cutting element 6 when the receivers are at rest and the crank arm 19 is so placed 75 upon the shaft 10 that when the knife 6 is out of operative contact with the edges 5 of the receivers 4, the carrier 3 and consequently the receivers will be advanced the requisite distance to bring the next one into 80 position to coöperate with the cutting knife.

By referring to Figs. 1, 3 and 4, it will be seen that the carrier 3 is so located in relation to the flow-block 1, that the stream is diverted, then cut and after being cut, 85 flows substantially into the center of the receptacle. This is aided by reason of the motion of the cutting element 6, down the inclined surface 5 of a receiver 4, since the cutting element positively forces the upper portion of the stream away from the surface 5 and toward the normal path of flow, as indicated in Fig. 4. The same then moves so that the next succeeding receptacle is beneath the flow-block and the stream of glass 90 is therefore drawn across the intervening edges of the receptacles. When the same become stationary the cutting knife descends and severs the glass, the lower cut-off end falling into the first receptacle and the upper 95 end into the next one, whence the above described cycle is repeated.

The receptacles 5 may be, themselves, molds in which the articles are formed, or may be receivers from which the glass may 100 be transferred to molds to be pressed or blown.

Having thus described this form of my invention, I do not wish to be limited to the precise details of form and arrangement of 110 parts illustrated, but what I claim and desire to protect by Letters Patent is:

1. A device for serving glass, comprising, means for producing a flowing stream of glass, a series of receptacles having inclined cutting faces and a cutting member movable upon said faces to coöperate therewith to sever said stream without interrupting its flow.
2. A device for serving glass, comprising means for producing a flowing stream of glass, a series of separate receptacles having inclined faces which contact exteriorly with each other, means for moving said receptacles intermittently, and a cutting member adapted to reciprocate upon the inclined face of each successive receptacle to sever said stream without interrupting its flow.
3. A device for serving glass comprising means for producing a flowing stream of glass, a series of receptacles having an upper portion of an interior wall of each inclined, means for moving the receptacles successively to charging position beneath the stream by intermittent movement, a cutter disposed at one side of the charging position of the receptacles and having a cutting edge adapted to be moved into the charging receptacle, and means for reciprocating the cutter in and out of the charging receptacle upon said inclined wall when the receptacle is at rest.
4. A device for serving glass comprising a series of receptacles having an upper portion of an interior wall of each inclined, means for moving the receptacles successively to charging position by intermittent movement, a cutter disposed at one side of the charging position of the receptacles and having a cutting edge adapted to be moved into the charging receptacle, and means for reciprocating the cutter in and out of the charging receptacle upon said inclined wall when the receptacle is at rest.
5. A device for serving glass comprising a series of receptacles, means for moving the receptacles successively to charging position by intermittent movement, a cutter disposed at one side of the charging position of the receptacles and having a cutting edge adapted to be moved into each receptacle successively, adjacent a wall thereto, and means for reciprocating the cutter in and out of the receptacles when they are at rest.
6. A device for serving glass comprising means for producing a flowing stream of glass, a series of adjacent receptacles, means for moving the receptacles to and from charging position whereby a charged receptacle in moving from the charging position, will divert the stream while an empty receptacle is moving into charging position, and means positioned at the diverted path of the stream and laterally from its normal path acting on the wall between the said empty and adjacent charge receptacles for severing the flowing stream of glass while the empty receptacle is in charging position.
7. A device for serving glass comprising means for producing a flowing stream of glass, a series of adjacent receptacles, means for moving the receptacles to and from charging position whereby a charged receptacle in moving from the charging position, will divert the stream while an empty receptacle is moving into charging position, and means positioned at the diverted path of the stream and laterally from its normal path acting on the wall of the empty receptacle while in charging position for severing the flowing stream of glass.
8. In a machine for serving glass from a flowing stream, means for diverting said stream into an inclined path, a cutting device, one element of which constitutes said diverting means, and another element which is adapted to move across the former to sever the inclined portion of the stream, whereby the oncoming stream is free to move to a vertical position out of contact with the mechanism.
9. In a machine for serving glass from a flowing stream, means for drawing said stream to one side of its normal flow, and a cutter adapted to sever the diverted stream and positively force the upper portion thereof toward its normal path.
10. In a machine for serving glass from a flowing stream, a movable part adapted to draw said stream to one side of its normal flow, and a cutting element coöoperating with said movable part to sever the diverted stream and positively force the upper portion thereof toward its normal path.
11. In a machine for serving glass from a flowing stream, a movable part having an inclined surface and adapted to draw said stream to one side of its normal flow, and a cutting element coöoperating with said movable part to sever the stream and positively force the upper portion away from said inclined surface toward its normal path.
12. In a machine for serving glass from a flowing stream, a series of adjacent receptacles, means for moving said receptacles into charging position and to deflect the charging stream flowing into a charged receptacle and means for severing the deflected stream and forcing the upper portion thereof into the adjacent receptacle when in its charging position.

Signed this 31st day of December, 1912.
ERNEST HOPKINSON.
